(57) **CLAIM**

The ornamental design for a projector, as shown and described.

DESCRIPTION

FIG. 1 is a perspective view of a projector showing my new design; and

FIG. 2 is a front elevational view thereof.

FIG. 3 is a fragmentary enlarged perspective view thereof along the lines 3-3 and 3'-3' of FIG. 1.

FIG. 4 is a fragmentary enlarged front elevational view thereof along the lines 4-4 and 4'-4' of FIG. 2.

FIG. 5 is an enlarged cross sectional view thereof along the line 5-5 of FIG. 4; and,

FIG. 6 is an enlarged cross sectional view thereof along the line 6-6 of FIG. 4.

The portions indicated in broken lines are for illustrative purposes only and form no part of the claimed design.

1 Claim, 5 Drawing Sheets
